AUTOMATIC VOLUME CONTROL CIRCUITS

Edward T. Dickey, Philadelphia, Pa., assignor to
 Radio Corporation of America, a corporation of
 Delaware

Application March 6, 1933, Serial No. 659,781

4 Claims. (Cl. 250—20)

My present invention relates to a novel and improved method of obtaining automatic volume control in radio receivers without recourse to changing the characteristics of the amplifier tubes.

In general, there are two types of automatic volume control arrangements adapted for use with radio receivers. In one of these types the characteristic of one or more of the tubes of the receiver, usually the amplifier, is regulated. In the other type the transmission of signal energy through the receiver network is regulated by controlling the high frequency coupling between two designated points in the receiver network.

As is well known to those skilled in the art, each of these types of automatic volume control is accompanied by certain advantages and disadvantages. The form of volume control arrangement involving the changing of certain of the operating characteristics of the tubes intended primarily for amplifier purposes has a number of disadvantages, among which are tendencies to produce cross-modulation and harmonics in the radio frequency amplifier.

Accordingly, it may be stated that it is one of the main objects of my present invention to provide an improvement in volume control arrangements for radio receivers, and particularly in automatic volume control arrangements, wherein, instead of changing the characteristics of the amplifier tubes, the transfer of radio frequency energy through a coupling capacity is controlled by a space discharge device functioning in cooperation with said coupling capacity as a variable high frequency energy shunting impedance.

The aforementioned coupling capacity may comprise a coupling condenser between two successive radio frequency energy points of the receiver, but it may also consist of an inherent inter-electrode capacity of one of the tubes of the receiver. Therefore, it may be stated that it is another important object of the present invention to provide an automatic volume control arrangement for a radio receiver wherein a radio frequency coupling capacity is used as the volume control instrumentality, the regulation of the transfer of energy through this capacity being accomplished by connecting to the capacity a variable shunting impedance, such as a space discharge device, and the conductivity of this impedance being automatically controlled by the direct current component of a rectifier plate current.

Another object of the present invention is to

provide in a radio receiver equipped with a rectifier, such as the detector of the receiver, and a preceding radio frequency amplifier, an automatic volume control network which comprises an electronic device connected with an element 5 providing radio frequency coupling capacity between the amplifier and rectifier, the rectifier direct current output being utilized to regulate the conductivity of the electronic device, and the latter functioning as a radio frequency shunting 10 path to ground.

Still other objects of the present invention are to improve generally the simplicity and efficiency of volume control arrangements for radio receivers, and to especially provide an automatic 15 volume control circuit, of the type wherein radio frequency coupling is regulated, which is not only reliable in operation, but economically manufactured and assembled in a radio receiver.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 diagrammatically shows a radio receiver embodying one form of the present invention,

Fig. 2 shows a modified form of the invention.

Referring now to the accompanying drawing wherein like reference characters in the different figures designate similar circuit elements, there is shown in Fig. 1 a conventionalized radio receiver. The source of signals 1, when the receiver is of the tuned radio frequency type, may include the usual grounded antenna circuit, and one or more tuned stages of radio frequency amplification. In the case of a superheterodyne receiver, the signal source 1 is to be understood as consisting of the antenna circuit, a stage of tuned radio frequency amplification if desired, and the usual local oscillator and first detector circuit. In any event, whether the receiver be of the tuned radio frequency type, or superheterodyne type, there will be impressed upon the tube 2 radio frequency signal energy of a desired frequency.

The tube 2 is shown as of the screen grid type, and includes an indirectly heated cathode, it being understood that the invention is not necessarily limited to this type of tube. Between the control grid electrode and the cathode is connected the 55

usual resonant input circuit 3, and the coil 4 in this input circuit is coupled, as at M, to the source of signal energy 1. The condenser 5 tunes the coil 3 to the desired frequency.

5 Where the tube 2 functions as an intermediate frequency amplifier of a superheterodyne receiver, then the condenser 5 remains of a fixed capacity value, and resonates the circuit 3 to the operating intermediate frequency. Of course, if the 10 receiver is of the tuned radio frequency type, then the condenser 5 will be variable for tuning the circuit 3 through the desired signal frequency range, such as the broadcast range, and will be uni-controlled, as is well known to those skilled 15 in the art, with the variable tuning condensers which may be used ahead of, or after, the tube 2.

The grid of tube 2 is maintained at a proper negative bias with respect to the cathode by means of the usual biasing network 6 disposed in the 20 grounded leg of the cathode of tube 2. The anode of tube 2 is supplied with a proper positive potential from a source B (not shown), the anode being connected to this source through the choke coil L₁.

25 The condenser C₁ functions as the sole coupling for radio frequency energy from the anode circuit of tube 2 to the resonant input circuit 3' of the succeeding rectifier tube 7. The tube 7 is also of the indirectly heated cathode type, and 30 the low radio frequency potential side of the tuned input circuit 3' is connected to the negative terminal of the source of grid biasing potential C (not shown). The tube 7 is generally designated as "rectifier", but it is to be clearly understood that 35 in the case of a tuned radio frequency receiver this tube functions as the usual detector and in the case of superheterodyne receiver the tube may function as the second detector. The tube 7 may, also, be another tuned radio frequency amplifier 40 stage.

45 The condenser 5' of input circuit 3', in the case of superheterodyne reception, fixedly tunes the circuit 3' to the operating intermediate frequency, and in case of tuned radio frequency circuits the condenser 5' will be uni-controlled with the condenser 5 for tuning the circuit 3' through the tuning range of the receiver.

The anode of tube 7 is connected to two independent paths. One of these paths includes the 50 audio frequency coupling condenser 8 to the succeeding stage, or stages, of audio frequency amplification, and the final reproducer. The other path includes in series the coupling resistor R, the source of anode potential B₁, and the volume 55 control bias resistor R₁.

60 The ungrounded terminal of the bias resistor R₁ is connected to the negative terminal of the source B₁, while the positive terminal of this potential source is connected to one side of the coupling resistor R. A condenser C₂ is connected in shunt with the bias resistor R₁ to provide the usual time constant network. The condenser C₃ is connected between the anode and grounded leg 65 of the cathode of tube 7 for the customary radio frequency by-passing function.

70 Between the two plates of condenser C₁ is disposed a central plate P which is grounded for radio frequency energy through a path which includes the lead 9, the electron discharge control tube 10, and the radio frequency by-pass condenser C₄. In other words, the central plate P is 75 grounded for radio frequency energy through the control tube 10. The control tube 10 is fed with proper anode potential from a source B₂ (not shown) through a choke L₂. This choke should

be sufficiently high in impedance so that the central plate P is not grounded through it (that is, through the choke L₂).

75 The control grid of tube 10 is grounded, and the cathode of the tube is connected to the ungrounded terminal of resistor R₁ through a path which includes the potential source B₃, and the adjustable tap 11. The positive terminal of the source B₃ is connected to the ungrounded side of condenser C₄, while the negative terminal of this potential source is connected to the tap 11. The latter tap is adapted to be moved along the bias resistor R₁ in order to predetermine the volume level at which the automatic volume control 10 action is to be maintained. That is to say, the tap 11 can function as a manual volume control, and at the particular setting of the tap 11 the signal energy impressed upon the rectifier tube 7 will be maintained substantially constant regardless 15 of variations in the signal energy collected by 20 the receiver.

25 As the voltage of the cathode of tube 10 is varied with respect to the grounded grid, the anode to cathode impedance of tube 10 is varied, and thus the resistance between the center plate P and ground is varied for radio frequency energy. Therefore, the radio frequency energy transferred across the coupling condenser C₁ is similarly varied, and thus the signal energy input to the rectifier tube 7 is regulated. The control voltage 30 applied to the cathode of tube 10 is obtained from the anode circuit of rectifier tube 7, and automatic volume control is secured since the anode current of this rectifier tube varies as a function of the 35 incoming signal strength.

40 The potential source B₃ with no signal energy impressed across the tuned circuit 3' keeps the tube 10 non-conductive, and the source B₃ is chosen so as to maintain the cathode of tube 10 positively biased with respect to the grounded 45 grid in such a manner that the tube 10 is biased close to cut-off. However, as the signal input to the tuned circuit 3' increases, the potential drop across the bias resistor R₁ increases, and the point on R₁ to which the tap 11 is connected becomes more negative. This results in the positive effect of the source B₃ being neutralized, with the result that the cathode of tube 10 becomes less positive with respect to the grounded grid thereby rendering the tube 10 more and more 50 conductive. It will thus be seen that with increasing signal input to the tube 7, the radio frequency energy shunted to ground from the central plate P increases.

55 Of course, the tube 7 need not be the detector of the receiver, but may be a special volume control tube functioning as a rectifier for the production of a direct current component which varies in accordance with signal energy fluctuations. Also, the direct current component in 60 the rectifier plate circuit need not vary directly with the signal energy variations in the rectifier input circuit. For example, there may exist an inverse relationship between the two. Such a state of affairs is shown in Fig. 2.

65 In this figure is shown a modification of the arrangement of Fig. 1, and only such tubes and associated circuits are shown which are essential to an understanding of this form of the invention. Thus, the radio frequency amplifier 2 70 is shown coupled, through the condenser C' to the rectifier tube 7. In this case, however, the usual grid leak 6' is utilized for providing rectification. In this type of rectifier, as is well known, the direct current component of the rec- 75

tifier plate circuit varies inversely with the signal energy variations in the tuned input circuit 3'.

The audio frequency signal component is taken 5 out of the plate circuit of the rectifier tube 7 through an audio frequency transformer M₁. The control tube 10, in this modification, has its cathode grounded, while its control electrode is connected to the positive terminal of source 10 B₃. The radio frequency coupling capacity which is regulated in this modification, comprises 15 the inherent capacity existing between the screen grid of tube 2 and the anode thereof. Accordingly, the anode of tube 10 is connected to the screen 2' of tube 2, and the positive screen grid bias for tube 2 is obtained through the choke L₂ the circuit 3' comprising the path through which the positive potential for the anode of tube 10 is supplied. The choke L₂ should be sufficiently 20 high in impedance so that it does not offer any grounding effect for the screen grid 2'.

It will, therefore, be seen that the modification shown in Fig. 2 comprises the grounding of the screen grid 2' of the amplifier tube 2 through a 25 variable impedance, this impedance consisting of the control tube 10. By impressing varying direct current voltages on the grid of tube 10, the resistance of the plate circuit of this control tube is varied, and necessarily the resistance from the 30 screen grid 2' to ground is varied. The amplification of tube 2 will increase due to regeneration effects within that tube circuit when a relatively high resistance is inserted between its screen grid and ground. Conversely, when a 35 very small resistance exists between its screen grid and ground it will have a minimum of amplification. In all cases the voltages on control grid, screen grid, plate and cathode of the amplifier tube 2 should be the normal values for optimum amplifier action.

It should be noted that the direct current resistance of the choke L₂ in Fig. 2 should be sufficiently small to affect the voltage on the screen grid 2' to a negligible degree when the tube 10 is drawing its maximum plate current. In order to avoid tendency towards oscillation, the tube 2 should either be a screen grid tube with relatively low mutual conductance, or else the circuits associated with it should be designed so as not to take advantage of all of its amplifier 45 possibility. Of course, in the arrangement shown in Fig. 2 when no signal energy is impressed on the tuned circuit 3', there will be a large flow of direct current in the plate circuit of tube 7, with the result that the grid of control tube 10 will be maintained highly negative with respect to the grounded cathode. When the signal energy impressed on circuit 3' increases, the flow of direct current will decrease, with the 55 result that the grid of tube 10 will become less negative, and the tube 10 thus becomes more conductive; that is to say, the resistance existing between the screen grid 2' and ground will then become smaller.

It is pointed out that the present invention is not merely applicable to the control of but a single amplifier stage. It is to be clearly understood that in each of Figs. 1 and 2 respectively

the plate circuits of the control tubes 10 can be connected for controlling several stages if desired. Furthermore, while I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. In combination, a radio frequency amplifier, a rectifier, said amplifier including a screen grid electrode, a control tube connecting said screen grid electrode to ground through its space current path to provide a radio frequency bypass path, and a direct current connection between the rectifier output circuit and a gain control electrode of said control tube for regulating the conductivity of said control tube sufficiently to vary the impedance of said bypass path.

2. In combination, a radio frequency amplifier, a rectifier, said amplifier including a screen grid electrode, a control tube connecting said screen grid electrode to ground, to provide a radio frequency bypass path and an adjustable direct current connection between the rectifier output circuit and a gain control electrode of said control tube for regulating the conductivity of said control tube sufficiently to vary the impedance of said bypass path to ground.

3. In a radio receiver including at least one radio frequency amplifier tube and a following rectifier tube, said amplifier tube being of the screen grid type, a capacitative path between the screen electrode of the amplifier and the rectifier input circuit, an electron discharge tube connected between said path and ground to provide a radio frequency by-pass path to ground for radio frequencies to be transmitted from the amplifier to said rectifier, and means for varying the impedance of said by-pass tube in response to variations in value of the direct current voltage in the rectifier output circuit, said capacitative path including the inherent capacity between the screen and anode electrodes of said amplifier, and said by-pass tube having its anode connected to the amplifier screen electrode.

4. In a radio receiver including at least one radio frequency amplifier tube and a following rectifier tube, said amplifier tube being of the screen grid type, a capacitative path between the screen electrode of the amplifier and the rectifier input circuit, an electron discharge tube connected between said path and ground to provide a radio frequency by-pass path to ground for radio frequencies to be transmitted from the amplifier to said rectifier, and means for varying the impedance of said by-pass tube in response to variations in value of the direct current voltage in the rectifier output circuit, said by-pass tube having its anode connected to said screen electrode and its cathode grounded, the last means including a direct current connection between the control grid of the by-pass tube and the rectifier output circuit.

EDWARD T. DICKEY.
